GOLF TEE

Siegfried Gordon Isserstedt, Toronto,
Ontario, Canada

Application February 2, 1946, Serial No. 645,075

3 Claims. (Cl. 273—33)

1

This invention relates to golf tees.

Golf tees have been produced in several different forms constructed from wood, plastic material and other composition, as well as metal. In substantially all cases, the tees have a general similarly, viz. a cup or cup-like element at the top designed to receive the spherical contour of the ball to form a base therefor and a pointed stem projecting downwardly therefrom usually from the centre of the cup-like portion.

When using the conventional tee in hard ground, it is very difficult to cause the tee properly to penetrate the ground. Moreover, when a firm penetration has been achieved and the tee is used in hard ground, the stem very often is broken. Furthermore, when a golf ball is supported by a conventional tee and it is desired to give the ball a low trajectory, a part of the rim of the tee disposed forwardly of the ball in the direction of the drive obstructs the entirely free movement of the ball. This has some effect on the flight of the ball and more particularly when the tee is in hard ground and does not yield and where the cup portion is relatively deep, as is the case in some constructions employing a head of substantial diameter in order to permit easy seating of the ball. To overcome this obstruction, tees are sometimes made with a narrower head in order to achieve a shallower cup, but this in turn makes it difficult to balance the ball on a tee when it is not introduced to the ground absolutely vertically.

It is desirable when using a tee to introduce it to the ground each time to a substantially uniform extent in order that the player may achieve uniform results in his drive at each tee. It has previously been proposed to provide a tee with a head having a circumferential projecting shoulder so that the shank of the tee may be introduced to the ground until the shoulder of the head engages the ground. This makes it possible to tee the ball at the same height each time. It has also been proposed to employ a circular rubber tee forming in effect a pedestal which is placed upon the ground and which will support the ball above the ground to a uniform distance in each case.

In this first type of special tee, the head is very often broken off due to the deep penetration of the shank in the ground, whereas in the latter type of special construction the tee is very often driven away with the ball and sometimes lost but at least making it necessary for the user to look for it.

The present invention avoids the general dis-

2

advantages of the prior art, as above indicated, and provides further advantages. It is an object of the present invention to form a new type of tee which will make it easier to introduce to the ground and notwithstanding that the ground may be hard.

A further object of the invention is to provide a simple form of tee which may be produced very inexpensively, stamped and formed from sheet material.

A further object of the invention is to provide a tee having a support for the ball so formed that it does not present any obstruction to the flight of the ball as it leaves the tee.

15 A further object of the invention is to provide a tee which may be readily nested thereby to provide for a neat package of tees.

20 A further object of the invention is to provide a simple tee construction employing a stop means having a surface disposed at right angles to the longitudinal axis of the tee and a bladed shank such that the tee will tend automatically to assume a normal vertical position when pushed into the ground, and which will always 25 maintain the ball spaced from the ground to a substantial uniform extent.

20 A further object of the invention is to provide a tee of this kind which will provide a flat surface of substantial area usable if desired for advertising material.

30 With these and other objects in view the invention generally comprises a single piece of flat material cut to form a pointed blade, the upper portion of which is bent to form a pair of spaced apart slightly inclined surfaces formed at the top edge of the material and designed firmly to support the ball. In particular, the pointed blade is so formed in the construction that the edges thereof are substantially aligned 35 with the path of flight of the ball, and the bent portion thereof in effect forms a wing providing at its lower edge a stop means for disposing the head of the tee at a predetermined uniform distance from the ground while forming the means 40 also for guiding the tee accurately into the ground.

45 The invention will be clearly understood by reference to the following detailed specification taken in conjunction with the accompanying drawings.

In the drawings,

Fig. 1 is a perspective view of the improved form of tee according to the present invention.

Fig. 2 is a schematic view of this tee disposed

in the ground and illustrating the manner in which a golf ball is supported thereon.

Fig. 3 is a top plan view of the tee.

Fig. 4 is a schematic view showing the manner in which the tees may be nested together; and

Fig. 5 is a front elevation of a tee according to the present invention and illustrating a slightly alternative form of construction.

Referring to the drawings, A indicates the tee as a whole which is formed from a single sheet of formable material which may include metal, plastic or other suitable material. This is stamped to form a blade 10 which is tapered to form a lower point 11. The upper edge of the blade, as indicated at 12, forms part of the support for the ball. The complete support is formed by bending a lateral upper wing 13 of the blank to be disposed in spaced apart relation to the blade 10 so that the forward edge 14 of the wing is disposed in line with the forward edge of the blade 10 when viewing the tee in side elevation. The lower edge 15 of the wing 13 is disposed substantially at right angles to the longitudinal axis of the blade and forms a stop designed to engage the ground and maintain the supporting head of the tee spaced uniformly from the ground during each use of the tee. It also forms a means of accurately locating the tee in the ground. In this connection, it will be appreciated that the edges of the blade 10 will tend to cut through the ground. Therefore, when the tee is pressed into the ground and the lower edge 15 of the wing 13 engages the ground, the rear edge of the blade 10 will tend to cut through the ground if the blade is introduced thereto so that the tee would be canted rearwardly and vice versa if introduced so that the front portion of the tee would tend to cant forwardly.

The upper supporting surface of the tee provided by the upper edges of the blade and the wing respectively is slightly rearwardly and downwardly inclined and then is projected upwardly in the form of a shoulder 16. Consequently no difficulty will be experienced in balancing the ball on the tee as it will immediately tend to seek a position of rest engaging the shoulder 16, while the forward portions of the support do not form, as in the case of the ordinary tee, a rim or other obstruction which would tend to affect the projection of the ball from the tee in any way. In particular, as will be noted from a consideration of Fig. 3, the supporting edges in spaced apart relation in effect form a guideway from which the ball may be cleanly projected.

Preferably at the point of connection between the wing 13 and the blade 10, the material is outwardly curved or flared as indicated at 17 in effect to form a bead-like channel which will mate with the corresponding formation on another tee so that the tees may be readily nested or stacked as indicated in Fig. 4, and will be held from inadvertent dislodgment by wedging.

In an alternative form of construction, a wing may be formed of greater depth and a lower portion thereof turned inwardly to form a flat shoulder 18 of greater area than the normal edge 15 (Fig. 1).

It will be readily apparent that this type of tee

presents a number of advantages. In the first place, it does not form any obstruction to the projection of the ball from the tee as above indicated, while it also forms a firm base for the ball which will not require special adjusting of the tee properly to balance the ball. This is due to the fact that it will automatically tend to seat itself properly. Apart from this, however, it will be apparent that the tee will operate to prevent breakage of the shank which often occurs in normal tees since even in hard ground and if the tee is hit, the blade thereof will tend to cut through the ground.

What I claim as my invention is:

1. A golf tee comprising a blade pointed to form a shank designed to pierce the ground, said blade in its upper portion having an integral wing disposed to overlie a face of the blade in spaced apart relation thereto, the upper edge of said wing and the upper edge of said blade being disposed in substantially the same plane and jointly forming a support for a golf ball, said wing being connected to the blade along one edge thereof, the opposite edge of the blade and the opposite edge of the wing being free from one another, said opposite edges being disposed at the front of the tee forming a channel therebetween opening towards the front of the tee to provide, in effect, a guideway to cause free projection of the ball from the tee when said ball is struck, said upper edges of the blade and the wing being slightly inclined rearwardly and downwardly, said tee being formed with an upwardly projecting shoulder substantially at the point of connection between the wing and the blade and forming with said upper edges a firm seat for the ball.
2. A golf tee as claimed in claim 1 in which the tee is outwardly flared in the area of the connection between the wing and the blade to form in effect a bead channel for wedging said tees in nested relation.
3. A golf tee comprising a blade pointed to form a shank designed to pierce the ground, said blade in its upper portion having an integral wing disposed to overlie a face of the blade in spaced apart relation thereto, the upper edge of said wing and the upper edge of said blade being disposed in substantially the same plane and jointly forming a support for a golf ball, said wing being connected to the blade along one edge thereof, the opposite edge of the blade and the opposite edge of the wing being free from one another, said opposite edges being disposed at the front of the tee forming a channel therebetween opening towards the front of the tee to provide, in effect, a guideway to cause free projection of the ball from the tee when said ball is struck.
